CONTROLLABLE ELECTRICAL DELAY MEANS

John W. Tilley, Philadelphia, Pa., assignor to
Phileo Corporation, Philadelphia, Pa., a corpora-
tion of Pennsylvania

Application September 20, 1944, Serial No. 554,960

6 Claims. (Cl. 313—157)

1

The present invention relates to space discharge apparatus and concerns particularly apparatus of the type in which an electric emission beam or electronic beam is produced.

An object of the invention is to provide improved methods and apparatus for producing time delay effects.

Another object is to provide improved methods and apparatus for controlling delay of high frequency signals without employing filter networks.

Another object is to provide arrangements for producing the same absolute delay for all frequency components of a signal.

Still another object is to provide arrangements for utilization or for control of transit time effects.

An additional object of the invention is to provide means in electron beam apparatus for lengthening the beam which may be utilized within a given space.

Still another object of the invention is to provide transit time apparatus in which the length of an electronic beam may be varied to vary time delay of the signal or for phase modulation.

Other objects of the invention are to provide means for varying the length of an electronic beam spiral for varying the tightness or pitch of such a spiral and for varying the radius of such a spiral.

A further object of the invention is to provide means for multiplying the effective length of the path of a stream of electrons.

Other and further objects, features and advantages of the invention will become apparent as the description proceeds.

In carrying out the invention in one of the preferred embodiments thereof, an evacuated tube or the like is provided having a concentric electrode arrangement with a cathode at the center, a ring-shaped anode and means for producing a magnetic field having a magnetic axis substantially coaxial with the anode and the cathode of the tube. Suitable beam forming and focusing electrodes are provided so that, disregarding the magnetic field, an electronic beam or a plurality of electronic beams tends to leave the cathode and to travel radially toward the anode. As a result of the action of the magnetic field, however, the paths of the electrons are twisted or if a single beam is employed, the electronic beam is twisted or coiled into a flat spiral form. Inasmuch as the beam forming and focusing electrodes impart a constant velocity to the electrons, the transit time of the

2

electrons in traveling from the cathode to the anode or collector is very greatly increased since the path has been lengthened from a simple radius to a spiral, the number of convolutions of which may be made very great by selecting the magnetic field of sufficient strength.

If an intensity controlling grid or control electrode is provided with a signal or carrier voltage applied thereto, the signal will be received by the collector anode with a time delay determined by the transit time of the electrons. Phase modulation of such a signal or carrier may be produced by varying the length of the electronic path, for example by varying the strength of the beam-twisting magnetic field.

The path of an electron or the shape of an electronic beam is made to take the form of a spiral. The spiral may either be a flat one in a single plane forming what is known as a "pancake coil" or may take any other spiral form desired such as along the surface of a cone or along the surface of a cylinder, for example, in the latter case forming what is known as a "helix" or "helical spiral."

The length of electron path and accordingly the transit time of the electrons may be varied by varying the length of the spiral regardless of the shape thereof. This may be done either by means of varying the strength of a beam twisting magnetic field as already mentioned or also by other means such as by a device for distorting the electron beam path such as electrostatic deflection means, for example.

A better understanding of the invention will be afforded by the following detailed description considered in conjunction with the accompanying drawings, and its scope will be set forth in the claims.

In the drawing,

Fig. 1 is a schematic diagram of one embodiment of the invention representing an elevation with certain portions of the interior of the apparatus in section to leave other parts visible.

Fig. 2 is a view, looking from above, of a cross-section of the apparatus of Fig. 1 represented as cut by a plane 2—2' indicated in Fig. 1.

Fig. 3 is a view corresponding to Fig. 1 illustrating an embodiment of the invention in which electrostatic beam deflection is employed for modulation purposes, and

Fig. 4 is a schematic diagram of an embodiment of the invention in which the electronic beam takes a "helical" or "corkscrew" form.

Like reference characters are utilized throughout the drawing to designate like parts.

The apparatus forming an illustrative embodiment of the invention as illustrated in Figs. 1 and 2 comprises a relatively flat circular evacuated envelope 11, assumed to be composed of glass for simplicity in the explanation and illustration, containing electron emitting means such as a cathode 12 in the form of a cylinder at the center of the envelope 11, and a ring-shaped anode or collector 13 which is substantially coaxial with the cathode 12. Suitable beam forming and focusing elements of conventional form may be provided for confining the electron emission to a path along a plane substantially intersecting the envelope 11 perpendicular to its axis 14. Such electron directing and beam forming elements may take the form, for example, of a substantially tubular shield 15 surrounding the cathode 12 and having a radial opening 16 for projecting a beam of electrons 17 which will tend to move radially except for the means hereinafter to be described.

For controlling the intensity of the electron beam, that is the number of electrons leaving the cathode 12 at a given time, a beam intensity control grid 18 may be provided which surrounds the cathode 12 if no individual beam is employed, or may merely be placed in front of the opening 16 in the shield 15 if such an element is provided. If desired, a constant velocity grid 19 may also be provided, which is analogous to a focusing anode or lens member of a conventional cathode-ray oscilloscope tube.

For twisting the electron beam 17, or for correspondingly twisting the paths of individual electrons issuing from the cathode 12, in case no beam forming element 15 is provided, a magnetizing member such as a permanent magnet or a pair of pancake coils 21 and 22 is provided, having a magnetic axis lying along or parallel to the axis 14 of the cathode 12 and the anode 13, the coils being on opposite sides of the tube.

For maintaining the shield 15 and the constant velocity grid 19 at suitable potentials, sources of unidirectional voltage such as batteries 23 and 24 may be provided, and a power supply source is provided for energizing the anode 13 which may take the form of an additional battery 25 connected in series with the lower voltage batteries 23 and 24.

If the apparatus is to be employed for reproducing a grid signal in the anode circuit, a load resistor 26 may be connected in series with the anode 13 to the positive terminal of the power supply 25, and conductors 27 and 28 may be connected across the ends of the load resistor 26 for supplying a signal receiving device represented by a load 29.

For impressing a signal upon the control grid 18, a signal input source 31 represented by a rectangle may be provided, or if the apparatus is to be utilized for producing phase modulation of a carrier, a carrier source or exciter may represent the input source 31.

If it is desired to provide adjustability of the delay in the signal applied to the control grid 18 as it reappears at the output conductors 27 and 28, means are provided for varying the strength of the beam-twisting magnetic elements 21 and 22. For example, the elements 21 and 22 may take the form of pancake coils connected in series to modulating voltage source 32. As a result of the magnetic field H produced by the solenoid coils 21 and 22, in a direction normal to the path of the electron beam

11, the electrons are diverted from what would otherwise be a radial path from the cathode 12 to the anode 13 and are twisted into the spiral form shown in Fig. 2, the outer portion of the spiral being represented by the reference numeral 17'. The pitch or tightness of the spiral depends upon the strength of the magnetic field H , and accordingly the point 33 at which the beam 17' impinges upon the ring cathode or collector 13 is determined by the strength of the magnetic field H produced by the modulating voltage source 32.

For convenience, a single spiral beam 17' or the spiral path 17' of a single electron has been shown. It is to be understood, however, that where a relatively large output is required it may be preferable to allow the electron emission to take place in all directions radially from the cathode 11 parallel to the plane of the tube 11, that is the plane of the top or bottom surface of the tube 11. The same principle of operation will take place as before, however. Even though there may be innumerable spiral paths corresponding to the path 17', each such path will have a linear dimension or length, and consequently an electron transit time determined by the strength of the magnetic field H . If precision is employed in the construction of the tube and the electrodes, all of such paths should strike the ring anode 13 at substantially the same time, and accordingly a delayed signal appears at the anode 13 which is a counterpart of the signal applied to the intensity control grid 18. Some form of beam forming electrode will, however, still be desirable in order to concentrate the electrons into the space between the planes represented by the top and bottom edges 34 and 35 of the ring anode or collector 13.

40 The time of travel of electrons from the velocity control grid 19 to the anode 13 in the arrangement of Fig. 1 will be in direct relation to the magnetic field strength of the coils 21 and 22 up to a point approaching the cut-off of plate current, and this is accomplished with a minimum number of electrodes.

In connection with Figs. 1 and 2, an arrangement has been described for producing modulation or for adjusting signal delay by varying the strength of the beam twisting magnetic field to vary the length of the beam or of the spiral electron path; however, the invention is not limited thereto. The effective length of the beam path may also be varied by distortion of the shape thereof. For example, the plane spiral 17' of Figs. 1 and 2 may be distorted into conical form so as to lie along the surface of a cone of greater or less angle according to the strength of a modulating voltage in order to produce variable delay. An arrangement for accomplishing modulation in this manner is illustrated in Fig. 3. The corresponding elements of Figs. 1 and 3 have been designated by the same reference numerals. The coils 21 and 22 may be connected to a source of constant direct current 70 as shown or permanent magnets may be provided in the arrangement of Fig. 3 for producing a constant field H .

In place of the annular or ring shaped collector anode 13, a disc shaped anode collector 13' may be provided. For distorting the shape of the spiral path 17' of Figs. 1 and 2, washer-shaped deflecting electrodes 36 and 37 may be provided. The beam deflecting electrodes or deflection plates 36 and 37 are mounted near the

Upper and lower ends of the cathode 12 and are directly connected or coupled to the modulating voltage source 32. In order to minimize defocusing effect of the anode 13', a second complementary anode 38 may be provided having substantially the same shape and size as the anode 13' but located near the lower surface instead of the upper surface of the tube 11, or vice versa, but preferably the anode 38 is maintained at a potential higher than that of the collector anode 13' by suitable means such as by means of a supplementary voltage supply or battery 39 connected between the anode 38 and the positive terminal of the power supply 25 of the anode 13'. It will be understood, of course, that if preferred, both of the anodes 13' and 38 may be connected in the load circuits, that is in series with the resistor 26 so that an input of either polarity from the modulating voltage source 32 will produce a phase modulation in the same direction in the output signal taken from the conductors 27 and 28.

In the arrangements of Figs. 1 and 3 in which the magnetic field H is caused to pass parallel to the axis 14 of the tube or envelope 11, normal to the radii emanating from the cathode 12, the twisting of the electron paths into spirals gives rise to a circular component of electric current owing to the moving electrons, which in turn produces a magnetic field which acts parallel to the magnetic field H but in the opposite direction. However, the electric current effect of the moving electrons is relatively small and is compensated by the use of a magnetic field H of adequate strength.

If desired, the beam forming shield 15 may be modified in construction and in the arrangement of its aperture 16' in such a manner that electrons are allowed to issue only at a small point and would travel within a single plane, namely the horizontal center plane of the tube 11 were no modulating voltage applied to the deflecting plates 36 and 37. The presence of a small direct voltage between the plates 36 and 37 tends to warp the electron beam from a spiral path in such a horizontal plane so as to follow a path of a conical spiral as the result of which the end of the conical spiral beam 17' strikes the anode 13' at a point 33'. A sufficient voltage to warp the electron beam path into the shape represented by the conical spiral 17'' is provided by a deflecting circuit bias voltage source such as a battery 41.

If the deflecting voltage is increased as the result of a signal applied by the modulating voltage source 32, the conical spiral 17' is further distorted from a flat plane and follows the surface of a cone of sharper apex angle as represented by a conical spiral path 42 impinging upon the cathode 13' at a point 43. Inasmuch as the radial pitch of the electron beam is relatively unchanged by the variation in modulating voltage, the path of the beam is made shorter as the result of the decreased radius, since the point 43 is closer to the center of the tube and the cathode 12 than the point 33'. Thus, in the arrangement of Fig. 3, variation in transit time effect is accomplished by varying the radius of the spiral beam to vary the length thereof as the result of the warping of the beam into a cone of sharper apex angle.

In the arrangements thus far described, the electrons would travel in radial paths unless twisted into spiral paths by the transverse magnetic field. However, the invention is not lim-

ited thereto, and includes arrangements in which the electrons are twisted from some other normal path into a spiral path. For example as illustrated in the arrangement of Fig. 4, electrons would normally follow a substantially axial path through a relatively long tube 44 unless twisted into a spiral or corkscrew form by a magnet 45 surrounding the tube 44 and having a magnetic axis substantially coincident with the longitudinal axis of the tube 44.

The tube 44 may include a conventional electron gun comprising such elements as an indirectly heated cathode 46, a conventional intensity control grid 47 adapted to be coupled to a signal input source represented by terminals 31' and a screen grid or focusing electrode 48 held at a suitable positive potential by means of a voltage source represented as a battery 49.

At the opposite end of the tube 44, there is a conventional collector anode 51 lying in a plane substantially perpendicular to the axis of the tube 44 and connected to an anode voltage source represented as a battery 52 with a load resistor 26 connected in series with the voltage supply 52.

Where modulation or adjustment of signal delay is to be accomplished electrostatically, the magnet 45 may take the form of a tubular permanent magnet composed of suitable high coercive force magnetic material such as aluminum, nickel, cobalt alloy, for example, or it may take the form of a solenoid or coil of current-conducting wire connected to a source of constant direct current represented by a battery 53. When the magnet 45 is used in this manner, it serves to lengthen the path of the electrons or to increase the transit time of the electron beam 55 between the cathode 46 and the collector anode 51. The electron gun, comprising elements 46, 47 and 48, is preferably so arranged as to produce electron beam deviating slightly from the axis of the tube 44 and the magnetic axis of the magnet 45 or the electron gun is arranged to produce a divergent cone of electron rays in order that the electron streams will have a component normal to the magnetic axis of the magnet 45, whereby twisting action may be produced.

Where the modulation is to be accomplished magnetically, the source of magnetizing current 53 is made variable in response to modulation or a separate source is connected across a current limiting resistor 56 in series with the constant current source 53 and the solenoid coil 45. Terminals 32' for connection to a modulating voltage source such as the source 32 in Figs. 1 and 3 or some other source of a delay control voltage, may be connected directly to the solenoid coil 45 or may be connected through an impedance-matching transformer 57.

The tightness of the spiral beam 55, that is the pitch and radius, are varied by varying the strength of the magnetic field produced by the solenoid 45 in response to variations in the input signal through the terminals 32'. A resultant variation in transit time of the electrons varies the delay in the signal appearing across the load resistor 26 serving as a counter-part of the signal supplied at the intensity control grid 47 through the signal input terminals 31'.

If electrostatic delay control or phase control is desired instead of magnetic, a pair of velocity control electrodes 58 and 59 may be provided which are preferably relatively close to the electron gun and to the anode 51 respectively in order to exert the maximum control over electron velocity. In this case the impedance matching

transformer 57 is connected to the electrodes 58 and 59 instead of to the solenoid coil 45, and a constant current is supplied to the coil 45 for producing a relatively long helical-electron beam path 55. To represent the change over from one form of modulation to the other, a double-throw, double-pole switch 61 has been shown having a pair of blades 62 connected to the impedance matching transformer 57, having one pair of stationary contacts 63 connected across the resistor 56 and having two other stationary contacts 64 and 65 connected to the velocity control electrodes 58 and 59 respectively. When the switch blades 62 are moved from the position illustrated to a right hand position making connection with the stationary contacts 64 and 65, modulating or delay-controlling voltages 180 degrees apart are applied to the electrodes 58 and 59, but preferably a bias source 66 is provided for preventing the electrodes 58 and 59 from drawing current. When the electrodes 58 and 59 are to be utilized, the bias source 66 is connected to a tap 67 of a secondary winding of the transformer 57 by closing a switch 68.

It will be understood that the coils 21-22 in Fig. 1 and the magnetic beam twisting coil 45 in Fig. 4 may be so shaped as to produce any desired variation in magnetic field strength along the ordinary electron path which would exist if the magnetic coils were not present. For example in the case of the coil 45 of Fig. 4, the ends of the coil may be tapered as at 45a so as to cause the magnetic field strength to increase gradually as the beam 55 enters the magnetic field and to cause the magnetic field strength to recede gradually again as the beam leaves the field of the coil 45 in order to cause the beam 55 to enter and leave the helical spiral form gradually.

Preferably suitable means are provided for refocusing and straightening the spiral electron beam 55 before it reaches the cathode 51. For example, a refocusing electrode 69 may be provided held at a suitable potential by a battery 71. With the change over switch 61 thrown to the right hand position making contact with the contacts 64 and 65, the modulating voltage source 32 is in effect connected in push-pull unbalanced relation to the velocity control electrodes 58 and 59. The permanent magnet or the constant current solenoid magnet 45 serves to supply a constant twist to the electron beam 55 for a given electron velocity, and the transit time is then varied by the variation in potential of the electrodes 58 and 59. The variation in velocity also has some effect on the twist of tightness of the helical-electron path, and accordingly variation in signal delay or phase modulation of the signal applied at the terminal 31' is produced by variation in voltage applied at the terminal 32'.

Certain embodiments of the invention and certain methods of operation embraced therein have been shown and particularly described for the purpose of explaining the principle of operation of the invention and showing its application, but it will be obvious to those skilled in the art that many modifications and variations are possible, and it is intended, therefore, to cover all such modifications and variations as fall within the scope of the invention which is defined in the appended claims.

I claim:

1. An electron discharge device comprising in combination an emitter for projecting electrons radially with respect to an axis, an intensity control electrode in front of the emitter, a constant 75

velocity electrode in front of the intensity control electrode, a pair of beam deflecting electrodes coaxial with respect to said emitter in the form of washers mounted at the ends of the emitter in planes transverse to said axis, and a collector transverse to said axis.

2. An electron discharge device having an axially located emitter for projecting electrons radially with respect to the axis of said device, a collector anode lying in a plane substantially normal to said axis and near one end of said emitter, means for setting up a magnetic field within said device in a direction parallel to said axis, whereby said electrons are caused to traverse a spiral path lying along the surface of a cone so as to impinge upon said collector anode, and an intensity control electrode coaxially disposed with respect to said emitter and adapted to vary the emission intensity of said emitter in accordance with a signal applied to said control electrode.

3. An electron discharge device having an axially located emitter for projecting electrons radially with respect to the axis of said device, a collector anode lying in a plane substantially normal to said axis and near one end of said emitter, means for setting up a magnetic field within said device in a direction parallel to said axis, whereby said electrons are caused to traverse a spiral path lying along the surface of a cone so as to impinge upon said collector anode, and a pair of deflection plates disposed parallel to said collector anode and lying on either side of the normal path of projected electrons.

4. A cylindrical electron discharge device having a longitudinal axis, an emitter of radially projected electrons located in substantial coincidence with said axis, a collector anode concentric with said axis and extending radially outward therefrom near one end of said emitter, a pair of deflection plates of substantially washer form also extending radially outward from said axis, said plates being disposed respectively near the ends of said emitter.

5. A device according to claim 4, further comprising a cylindrical electron-permeable control electrode disposed in coaxial relation with said emitter and adapted to vary the flow of electrons between said emitter and said collector anode.

6. An electron discharge device of generally cylindrical configuration having a longitudinal axis and comprising: an emitter of radially projected electrons, said emitter being located in substantial coincidence with said axis; a collector anode concentric with said emitter and extending in a plane normal to said emitter and near one end thereof; means for maintaining said collector anode at a positive potential with respect to said emitter, thereby causing electrons projected from said emitter to flow toward and impinge upon said collector anode; means for producing a magnetic field of predetermined flux density in a direction parallel to said axis, whereby said electrons are caused to traverse a spiral path between said emitter and said collector anode; and a pair of deflection plates disposed parallel to said collector anode and lying on either side of the normal path of projected electrons.
